UNITED STATES PATENT OFFICE.

GEORGE F. HENSEL, OF PHILADELPHIA, PENNSYLVANIA.

DESIGN FOR FRINGE.

SPECIFICATION forming part of Design No. 16,932, dated October 12, 1886.

Application filed June 7, 1886. Serial No. 204,428. Term of patent 14 years.

To all whom it may concern:

Be it known that I, GEORGE F. HENSEL, a citizen of the United States, residing in Philadelphia, Pennsylvania, have invented a new and original Design for Fringe Heading or Trimming, of which the following is a specification.

My design is shown in the accompanying drawings, the figures of which represent different forms of fringe or trimming, all embodying the essential features of the design.

The design comprises the upper and lower close bands, *a* and *b*, and the intervening open-work band, *d*. This open-work band is the leading feature of the design, and it consists of pillars crossing from the band *a* to the band *b*, these cross-pillars being substantially parallel and being of different widths, the wide and narrow pillars alternating with each other. The cross-pillars are such as to present a close or solid effect, the individual strands not being separated or prominently noticeable. The bands *d* may have at intervals close blocks *f*, as in Figure 1; but this is a minor feature of the design, and is not shown in Figs. 2 and 3.

The order of alternation of the wide and narrow pillars may be varied without departing from the essential feature of the design,

the different views showing different arrangements of the wide and narrow pillars within the general scope of the design.

In fringes the pendent portion of the fringe may be either straight or looped, my design having no reference to this portion.

I claim—

1. The within-described design for fringe heading or trimming, said design consisting of upper and lower close bands and an intervening open-work band with alternating wide and narrow cross-pillars, substantially parallel and presenting a close or solid effect, all substantially as described and shown.
2. The within-described design for a fringe heading or trimming, said design consisting of upper and lower close bands and an intervening band having blocks *f*, alternating with open-work portions composed of wide and narrow cross-pillars, all substantially as shown and described.

In testimony whereof I have signed my name to this specification in the presence of two subscribing witnesses.

GEORGE F. HENSEL.
